SAFETY RAZOR

Martin Glaberson, Ardsley, N.Y., assignor to Eversharp,
Inc., Milford, Conn., a corporation of Delaware

Filed Apr. 16, 1965, Ser. No. 84,835

Term of patent 14 years

(Cl. D22—3)

FIG. 1 is a top perspective view of a safety razor, showing my new design;

FIG. 2 is a side elevational view;

FIG. 3 is a front elevational view which is identical to the rear elevational view; and

FIG. 4 is a top plan view.

I claim:

The ornamental design for a safety razor, as shown and described.
